UNITED STATES PATENT OFFICE

2,490,136

DRESS WAIST AND DRESS SKIRT ENSEMBLE

Peter Joe, Sr., Crenshaw, Miss.

Application August 14, 1947, Serial No. 768,660

3 Claims. (Cl. 2—70)

1

This invention relates to a novel dress waist and dress skirt ensemble for women, and the primary object of the invention is to provide such an ensemble in which simple and efficient means is provided to support the skirt from the waist-line of the wearer and at a higher length when the wearer is in a standing position, and to support the skirt from the hips below the waist-line of the wearer and at a lower length so that the skirt will not climb above said higher length when the wearer assumes a sitting position.

A further object is to provide an ensemble of the above kind in which the supporting means embodies waist encircling bands carried by the waist and the skirt, the waist encircling band of the skirt being adjustable as to girth and coacting with the waist encircling band of the waist to support the skirt at the higher length.

The exact nature of the present invention will become apparent from the following description when considered in connection with the accompanying drawings, in which:

Figure 1 is a front view of the ensemble as it appears while being worn with the skirt supported from the waist-line of the wearer and at the higher length;

Figure 2 is a view somewhat similar to Figure 1 showing the skirt supported from the hips below the waist-line of the wearer and at the lower length;

Figure 3 is a fragmentary perspective view of the waist;

Figure 4 is a fragmentary perspective view of the skirt;

Figure 5 is a fragmentary vertical section taken on line 5—5 of Figure 1; and

Figure 6 is a fragmentary vertical section taken on line 6—6 of Figure 2.

Figure 7 is a plan view of one of the bands.

Figure 8 is an enlarged view of the ends of one of the bands.

Referring in detail to the drawings, B is a lady's dress waist of the blouse or any desired type and construction, said waist having a metallic body encircling band 5 secured on the inside thereof slightly below the waist-line. The band 5 may be formed of spring wire and bent to provide hook and eye means 6 at its meeting ends to fasten it about the body of the wearer. To secure the band 5 in place, a cloth strip 7 may be disposed over said band and sewed to the waist. An opening 8 is provided in the waist to facilitate insertion or removal of band 5 and connection or disconnection of its ends.

S is a dress skirt having a hem 9 at the top in 55

which is disposed a metallic body encircling band 10. At the sides of its upper portion, the skirt is split, and the edge portions of the skirt along the splits are overlapped as at 11 and adjustably connected by buttons 12 and button-holes 13 so that the upper edge portion of the skirt may be adjusted as to girth. The band 10 is formed of spring wire and bent to provide a hook 14 and eyes 15 at its meeting ends to similarly adjust said band and fasten it about the body of the wearer. An opening 16 is provided in the skirt to facilitate insertion or removal of band 10 and connection or disconnection of its ends.

When the ends of band 10 are connected, its 15 inside diameter is less than the outside diameter of band 5, so that by disposing band 10 at the waist-line and above band 5 as shown in Figures 1 and 5, the skirt will be supported at the higher length as desired when the wearer is in a standing position. By disconnecting the ends of band 20 10, the skirt may be lowered to the lower length and supported from the hips below band 5 as shown in Figures 2 and 6. When the latter is done, the skirt will not climb above the higher 25 length when the wearer assumes a sitting position.

The buttons 12 engaged in proper ones of the 30 buttonholes 13 will provide the proper girth at the upper edge of the skirt so as to insure support of the latter from the hips when the ends of band 10 are disconnected. When the skirt is raised and the ends of band 10 are connected, the girth of the skirt at its upper edge is reduced so as to support the skirt from the waist-line, the band 35 5 preventing downward movement of hem 9 and band 10.

From the foregoing description it is believed that the construction, manner of use and advantages of the present ensemble will be readily 40 understood and appreciated by those skilled in the art. Minor changes are contemplated, such as fall within the scope of the invention as claimed.

Having described the invention, what is 45 claimed as new is:

1. A dress waist and dress skirt ensemble for comprising a dress waist of the type which extends a short distance below the waist line, a metallic body encircling band secured on the inside of said waist slightly below the waist-line, said band having means at its meeting ends to fasten it about the body of the wearer, a dress skirt having a hem at the top, and a metallic body encircling band disposed in said hem, said skirt being split at the sides of its upper portion and pro-

vided with means along the edges of the splits to connect the portions at opposite sides of the latter and adjust said upper portion of the skirt as to girth, the second named band having means at its meeting ends to adjust the same as to girth and to fasten it about the body of the wearer, the inside diameter of said second named band being less than the outside diameter of the first named band when the ends of said first and second named bands are connected, so that by disposing the second named band at the waist-line and above the first named band, the skirt will be supported at a higher length, the girth of the skirt at the top being such as to cause the skirt to be supported from the hips below the first named band when the ends of the second named band are disconnected and the skirt is lowered to a lower length.

2. The construction defined in claim 1, wherein the waist and skirt are provided with openings

15

10

20

to facilitate insertion or removal of the bands with respect to said waist and skirt and to facilitate connection or disconnection of the ends of the bands.

3. The construction defined in claim 1, wherein said bands are formed of spring wire and bent at their ends to provide hook and eye means to connect the ends thereof.
